CLAIM

The ornamental design for a work platform, as shown and described.

DESCRIPTION

FIG. 1 is a perspective view of a work platform showing our new design;

FIG. 2 is a perspective view thereof, with the second step in its inoperative position;

FIG. 3 is a top plan view thereof;

FIG. 4 is a front elevational view, the rear being identical thereto;

FIG. 5 is a left side elevational view, the right side being identical thereto; and,

FIG. 6 is a bottom plan view thereof.

FIG. 1

FIG. 2

FIG. 3

FIG. 4

FIG. 5

FIG. 6
